UNITED STATES PATENT OFFICE.

CHARLES R. MEYER, OF DAYTON, OHIO.

ADJUSTABLE CURTAIN-SUPPORT.

949,936.

Specification of Letters Patent. Patented Feb. 22, 1910.

Application filed December 18, 1908. Serial No. 468,225.

To all whom it may concern:

Be it known that I, CHARLES R. MEYER, a citizen of the United States, residing at Dayton, in the county of Montgomery and 5 State of Ohio, have invented certain new and useful Improvements in Adjustable Curtain-Supports, of which the following is a specification.

My invention relates to window curtain 10 appliances, and particularly to an adjustable bracket or support for window blinds and curtains or portières.

The object of the invention is to simplify 15 the structure as well as the means and mode of operation of such devices whereby they will not only be cheapened in construction, but will be more efficient in operation, pleasing in appearance, easily and readily adjusted to accommodate different sizes of curtain rolls or rods, and unlikely to get out 20 of repair.

With the above primary and other incidental objects in view, as will more fully appear in the specification, the invention 25 consists of the devices, the features of construction, parts and combinations thereof, and the mode of operation or their equivalents, as hereinafter described and set forth in the claims.

Referring to the drawings, Figure 1 is 30 a view showing the upper portion of the window with the improved adjustable curtain support forming the subject matter hereof attached to the window-casing and 35 supporting the roller blind and the curtain rod. Fig. 2 is a perspective view of the adjustable supporting device removed from the window-casing. Fig. 3 is a detail perspective view partly in section, of the main 40 frame member viewed from the rear. Fig. 4 is a detail transverse sectional view showing in dotted lines the movement of the bracket for the purpose of longitudinal adjustment. Fig. 5 is a detail view similar to 45 Fig. 4, showing a slight modification.

Like parts are indicated by similar characters of reference throughout the several views.

Referring to the drawings, 1 is the window 50 surrounded by the casing 2 to which is secured the adjustable support which carries the roller blind 3 of ordinary construction and also the curtain rod 4 from which is suspended the curtain 5.

55 In constructing the adjustable support there is employed a main frame member 6

formed hollow or of a somewhat box-like construction. The frame member 6 is provided, in its forward side, with a longitudinal slot 7 along the lower edge of which 60 and on the inner side is located a longitudinal bead 8. On the outer face of the frame member 6 and parallel with the slot 7 is a series 9 of serrations. A similar series 10 of serrations is located on the inner side of 65 the frame member 6 and at the opposite side of the longitudinal slot 7. The frame member is provided with lugs or ears 11 by which it may be secured to the window-casing 70 by screws passing through said ears. 75 At the lower rear portion of the member is provided a projecting ledge 12 adapted to project beneath the heading of the window-casing enabling the frame to be adjusted square with the window and closing any 80 unsightly opening which might otherwise exist between the member and the window-casing thereby, improving the appearance of the device or it may be omitted if desired.

85 Slidably mounted in the member 6 is a supporting bracket which may be of any desired form, the usual supporting brackets for the roller blinds being shown at 13 and 14, while at 15 is shown an arm bifurcated or forked at its extremity and adapted to support the curtain rod 4. Whatever the shape of the supporting bracket may be, the connection of the same with the main frame member 6 will be identical. The upper portion 90 of the bracket is off-set as at 16 and extends within the frame member 6 through the slot 7 and is provided with one or more teeth 17 to engage the serrations 10 on the inner side of the frame member. Below the 95 slot 7, the bracket extends substantially parallel with the face of the frame member for a limited distance, and is provided with one or more teeth 18 adapted to engage the serrations 9 on the outer side of the frame 100 member. On the inner side of the bracket is provided a projecting lip 19 engaging over the bead 8 and forming a fulcrum for the bracket whereby the bracket will be capable of oscillation upon the longitudinal 105 bead 8 in addition to its sliding or longitudinal movement within the slot 7. There is provided at the rear of the main frame member 6 a longitudinal bar 20 forming a bearing for a spring which engages the bracket 110 at a point above its fulcrum and tends to move the bracket about its fulcrum point

and cause a simultaneous engagement of the teeth 17 with the serrations 10 and the teeth 18 with the serrations 9.

In Fig. 4 is shown a plunger 21 mounted in the bracket member and having a head 22 bearing on the bar 20. A helical spring 23 surrounds the plunger and is interposed between the bracket and the head 22. By this construction the head 22 of the plunger 10 forms the bearing surface which rides on the bar 20 as the bracket is longitudinally adjusted on the frame member. It is obvious, however, that the plunger 21 might be omitted and the spring 23 alone employed 15 which would then operate at one end on the bracket as now and at the opposite end on the bar 20.

When it is desired to shift the bracket in the main member in order to accommodate 20 a curtain roll of different length, the bracket is pulled out or away from the frame member as indicated in dotted lines in Fig. 4 oscillating on the bead 8 engaged by the lip 19 until the teeth 17 and 18 are disengaged 25 from the serrations 10 and 9, which movement also compresses the helical spring 23. The bracket may then be moved longitudinally within the slot 7 to the desired position and upon being released, the bracket will 30 return to normal position with the respective teeth 17 and 18 engaging the serrations 10 and 9 through the action of the spring 23.

In Fig. 5 is shown a modification in which the set screw 24 is substituted for the helical 35 spring 23. The set screw 24 engages the longitudinal bar 20 and by further operation tends to oscillate the bracket to engage it with the serrations in the same manner as the spring. In order to shift the bracket 40 with this construction, it would be necessary to first release the set screw 24. As shown in Figs. 1 and 2 both the bracket supporting the blind and the bracket supporting the curtain rod may be carried in the same frame 45 member as before stated the method of engaging these brackets with the main member is identical. However, if only one bracket is required the other may be omitted without in any way impairing the action of the 50 device.

From the above description it will be apparent that there is thus produced an adjustable curtain support of the character described, possessing the particular features of 55 advantage before enumerated as desirable, but which obviously is susceptible of modification in its form, proportion, detail construction, and arrangement of parts, without departing from the principle involved or sacrificing any of its advantages.

Having thus described my invention, I claim:

1. In an adjustable curtain support, a recessed frame member having a longitudinal slot therein, and a series of serrations

adjacent to said slot and on the inner side of said recessed frame member in combination with a bracket slidably mounted within said slot and adapted to engage the serrations, and a spring yieldingly holding the 70 bracket in engagement with the serrations, substantially as specified.

2. In an adjustable curtain support, a frame member having a longitudinal slot therein, serrations adjacent to said slot, a longitudinal bead adjacent to the slot, in combination with a movable bracket slidably mounted in said slot and adapted to fulcrum on said bead, means for moving said bracket about its fulcrum on said bead 75 80 whereby it will be caused to engage said serrations, substantially as specified.

3. In an adjustable curtain support, a recessed frame member having a longitudinal slot therein, two series of serrations 85 in said member located at opposite sides of the slot, one of said series being on the outer side of the member, and the other series on the inner side thereof, and a bracket adjustably mounted in said slot and adapted 90 to simultaneously engage both series of serrations, substantially as specified.

4. In an adjustable curtain support, a frame member, a supporting bracket slidably mounted on said frame member, said 95 bracket being capable of oscillation thereon in addition to its longitudinal movement, two series of serrations arranged on opposite sides of the fulcrum point of said bracket, and means tending to oscillate said bracket 100 on its fulcrum to cause it to simultaneously engage both said series of serrations, substantially as specified.

5. In an adjustable curtain support, a frame member having a longitudinal slot 105 therein, a longitudinal bead adjacent to said slot, oppositely disposed series of serrations on said frame member, one of said series being on the outer side of said member, the other series being on the inner side of the 110 member and located at the opposite side of the longitudinal slot, in combination with a supporting bracket slidably mounted in said slot, a lip on said bracket engaging the bead and forming a fulcrum for said bracket, 115 oppositely disposed teeth on the bracket at opposite sides of the fulcrum point and adapted to engage the respective series of serrations, and a spring engaging the bracket at one side of the fulcrum point and 120 adapted to yieldingly hold the teeth of the bracket in engagement with the respective series of serrations, substantially as specified.

6. In an adjustable curtain support, a frame member having a double series of horizontally directed serrations thereon, the series being oppositely disposed in relation to each other, and a supporting bracket slidably mounted on said frame, the said bracket having two oppositely disposed en- 125 130

gaging teeth on said bracket adapted to engage the serrations of the frame, substantially as specified.

7. In an adjustable curtain support, a frame member, two oppositely disposed series of serrations in said member, a supporting bracket slidingly mounted on said member and capable of an oscillatory movement in addition to its longitudinal movement, oppositely disposed engaging teeth on said bracket adapted to be engaged with and

disengaged from the serrations of the frame member by the oscillation of the bracket, substantially as specified.

In testimony whereof, I have hereunto set my hand this 10th day of December A. D. 1908.

CHARLES R. MEYER.
